UNITED STATES PATENT OFFICE.

BERNARD DOLAN, OF MINNEAPOLIS, MINNESOTA, ASSIGNOR TO WYMAN, PARTRIDGE & COMPANY, OF MINNEAPOLIS, MINNESOTA, A CORPORATION OF MINNESOTA.

BLOOMERS.

Application filed June 9, 1922. Serial No. 567,175.

To all whom it may concern:

Be it known that I, BERNARD DOLAN, a citizen of the United States, residing at Minneapolis, in the county of Hennepin and 5 State of Minnesota, have invented certain new and useful Improvements in Bloomers; and I do hereby declare the following to be a full, clear, and exact description of the invention, such as will enable others skilled 10 in the art to which it appertains to make and use the same.

My invention relates particularly to undergarments for women, misses and children, and is directed to the improvement of 15 a garment generally designated as "bloomers." The feature of construction involved in these bloomers is, however, capable of more general application in garments having the general characteristics or form of bloomers and, hence, it will be understood 20 that the term "bloomers" is herein used in a broad and liberal sense.

The results sought for and attained in my 25 invention are, generally stated, a highly efficient and comfortable garment that can be made with a minimum waste of cloth and which will require the least possible amount of stitching. My improved garment is so designed that it may be made from a single 30 normally flat piece of cloth and the edges of this single piece of cloth united by two seams, to wit: One running along the insides of the legs and the other running down the front and under the crotch. Preferably, 35 the garment thus formed will be gathered around the waist and around the bottoms of the legs.

In the accompanying drawings, which illustrate the invention, like characters indicate like parts throughout the several views.

Referring to the drawings:

Fig. 1 shows the completed garment or bloomers;

Fig. 2 is an enlarged fragmentary section 45 on the line 2—2 of Fig. 1;

Fig. 3 is an enlarged fragmentary section on the line 3—3 of Fig. 1;

Fig. 4 shows the flat single piece from 50 which the garment is cut; and

Fig. 5 is a perspective showing the piece of cloth folded and the stitching of its edges partly completed.

Referring first to Fig. 4, it will be noted

that the single piece of cloth 6 is cut with a waist-forming line 7, with front seam lines 8, with inside leg-seam-forming lines 9 and 9^a and with lower end leg-forming lines 10. As is evident, by reference to Fig. 4, the front seam edges 8 will be connected by front seam stitches 8', and the opposite 60 edges 9 are stitched to the curved inside leg-forming seam line or edge 9^a by inside seam-forming stitches 9'. This will give the general form to the garment, but the waist-line and the lower leg ends remain to be 65 gathered. In gathering the waistline, the cloth sheet 6 is preferably formed with darts 11, preferably formed by folding the cloth, but the complete upper edge of this waistline will be formed with a folded casing 12 70 in which an elastic waist-band 13 is preferably placed. The lower edges of the legs may be gathered by one or more elastic bands, or, as shown, each leg has two such elastic bands 14 and 15 placed, respectively, 75 in casings 16 and 17. The casings 12, 16 and 17 will, of course, be gathered by the elastic bands placed therein. The fullness in the seat of the garment is given chiefly by gathering of the waist-band in proportion to the 80 garment, but the gathering in the lower ends of the legs also contributes to this result. By reference to Fig. 4 it will be noted that the piece from which the garment is made has much greater transverse width at 85 its central portion than it has at its end portions. This feature also increases the fullness in the seat of the garment. Otherwise stated, the garment is made of such proportions as to give ample fullness in the 90 seat and then the waist and preferably also the lower ends of the legs are gathered by lateral or substantially horizontal contraction or gathering up of the cloth material. There is no gathering whatever of the garment vertically, that is, either by gathering of outside or inside leg seams or of the front seam of the garment.

The above described construction makes it possible to rapidly stamp the garments from cloth and to rapidly and efficiently stitch the edges of the cloth to form the garment. As already noted, only two seams are required.

The garment described has been made and 105 found satisfactory in all respects and its

manufacturing cost has been found to be exceedingly low, for reasons already clearly pointed out.

What I claim is:

- 5 1. A woman's garment of the bloomer type made from a single piece of material having in its lower central portion a crotch-forming notch and formed on its waist line with a convex curve merging at its ends into concave curves, said piece at its ends having straight edges stitched to the edges of said crotch-forming notch, and above said straight edges having concave curves joining straight edges extended to the ends of
- 10 15 the waist line of the garment, said latter noted curved and straight edges of the opposite sides of the piece being stitched together to form the front seam of the garment, the said garment-forming piece at its
- 15 20 transverse central portion measured from its crotch-forming notch to the waist line

edge being materially wider than the end portions of said garment-forming piece, whereby the garment is given increased fullness of the seat.

2. A woman's garment of the bloomer type made from a single piece of material having in its lower central portion a crotch-forming notch and formed on its waist line with a convex curve, said piece at its ends having edges stitched to the edges of said crotch-forming notch and above such edges having edges stitched together up to the waist line, the said garment-forming piece at its transverse central portion, measured from its crotch-forming notch to the waist line edge, being materially wider than the end portions of said garment-forming piece, whereby the garment is given increased fullness of the seat.

In testimony whereof I affix my signature.
BERNARD DOLAN.
